UNITED STATES PATENT OFFICE.

FRANK B. COMINS, OF NEWTON, MASSACHUSETTS, ASSIGNOR TO AMERICAN MOISTENING COMPANY, OF PROVIDENCE, RHODE ISLAND, A CORPORATION OF MAINE.

APPARATUS FOR CONDITIONING AIR.

Application filed August 7, 1923. Serial No. 656,243.

This invention relates to improvements in apparatus for conditioning air. More particularly it relates to apparatus which can be installed in separate units about a room and which operates to distribute moisture through the air and simultaneously to cause diverse circulation of the air, whereby conditions are made generally uniform throughout the room.

It is illustrated herein as it may be applied in a card room of a textile factory, or in like situation where it is desired to blow moisture in both directions along an alley between rows of machines, without blowing it sidewise or directly over such machines, which is not feasible because the moisture would there be injurious. Such are sometimes known as "double outlet" or "alley" type humidifiers; and so far as I am aware such machines have never before been made to distribute their output other than lengthwise of the alley, nor have they been made to handle air, independently of moisture, while the distribution of moisture is in operation.

It is an object of the present invention to provide for the more perfect conditioning of the air of such a room by the throwing of humidified air in specific directions, as for example in two opposite directions along the alley between the machinery, and to throw air of the room in other specific directions, as for example in opposite directions crosswise of the alley, thus throwing unhumidified air out over the machines, and by this indirect means inducing the circulation and general diffusion of humidity safely through the room, and getting it without danger to the machinery, into locations where it can have its desired effect on the stock that is being worked in the machinery. It is also the object to provide the other advantages which are characteristic of the invention disclosed, among which are the provision of means for circulating air in all directions, or at least in all of those specific directions for which the apparatus is adapted, even though no humidity is added to the air by the apparatus, and also to accomplish this by a single constantly running fan.

To this end the invention provides apparatus which is adapted to receive a supply of liquid water and by mechanical means arranged in the lower part of the apparatus

to raise and atomize it, while a downward current of air generated in the upper part of the apparatus is divided, deflected and projected from the center in several specific directions or zones, some branches carrying the atomized liquid and others not. In the specific form of apparatus illustrated there is provided a casing built around a vertical axis, having a fan, preferably at the open top of the casing, for driving air downward, and guide walls that divide and direct it horizontally, in separate currents. One of these air currents is merely unmoistened air of the room, and another current consists of air which acquires entrained moisture as it passes through the apparatus. The division of the air into these two services is effected within the apparatus, so that the single electric motor and fan which drive it are effective to project the air in radial streams which do or do not carry moisture, according to their individual arrangements, and which may in any event not be humidified by the shutting off of the water supply while the fan continues to propel said currents of air.

The drawings illustrate two forms of apparatus in which the invention may be embodied, and it will be understood that other variations may be made. It is intended that the patent shall cover, by suitable expression in the appended claims, whatever features of patentable novelty exist in the invention disclosed.

In the accompanying drawings: Figure 1 is a plan of apparatus embodying the present invention, in section on line 1—1 of Figure 2;

Figure 2 is an elevation, partly in medial section, showing an annular partition with a central opening, for dividing the air currents;

Figure 3 is an elevation of a portion of the apparatus, in section on line 3—3 of Figure 1;

Figure 4 is a plan in section on line 4—4 of Figure 5, showing a modification;

Figure 5 is an elevation of the same, partly in section; and

Figure 6 is an elevation in section on line 6—6 of Figure 4.

Referring to the drawings, a pan 10 is provided to which water may be fed by any suitable means as by a vertical pipe 11 whose enlarged top end 12 constitutes a central

water supply well, into which a worm 13 dips, within a tube 14, for lifting water to the under side of a rotating disk 15. This disk has a curved under surface, on which the clinging film of water is gradually raised and thrown outward by centrifugal force, so that it ultimately is thrown off from the periphery against a series of spatter plates 16 which break it into very fine globules capable of being entrained and floating in the air as fog. The said worm and disk are mounted on and rotate with a vertical shaft 18, higher up on which is an electric motor 20 which drives it and thereby also drives a rotary fan 22, as also a supplementary fan 23, if desired, both being arranged to propel air downward starting parallel to the direction of the axis. The apparatus will first be described herein on the assumption that this supplementary fan is omitted. Between the fan 22 and the disk is an annular partition 24 in whose central hole 25 and preferably just below it is the supplementary fan 23, if present. The partition 24 in a general way may be said to extend horizontally from the central hole 25 outward, although in practical construction it will ordinarily slope downward somewhat. And above this is an annular casing 26 in whose central hole 27 is the said fan 22, it being held at any desired height therein by the set screw 22'. The casing is placed above the partition 24 far enough to provide for the lateral currents of unhumidified air. The annular partition 24 is placed above the disk far enough to provide for those currents of air which are to bear the fog from the edge of the disk in predetermined directions, as for example, in opposite directions along an alley between machinery. Such air is driven by either or both fans downward through the central hole 25 of the partition, and then is deflected by the upper face of the said disk 15, which preferably is suitably curved for that purpose. This air is laterally confined so that its discharge is in limited radial zones and so that its escape in other than desired directions is prevented by vertical side walls 28.

Assuming fan 23 omitted, the arrangement of the disk, spatter blades and partition above, and the fan 22, may be according to any suitable arrangements for providing the generation and distribution of fog. It may be desired to prevent the partition having any function or character as a shield for preventing blasts of air striking the fog at the moment of its generation at the spatter plates, so that this part of the apparatus may function fully. To prevent such shielding care should be taken to see that the partition 24 is high enough above the disk and the spatter plates, and that the hole 25 is large enough, so that the full volume of air which is needed and is normal for carrying the fog

can pass the partition centrally, and flow freely out between it and the disk. The additional output of the fan, which is to be distributed unhumidified, in that case bears no direct relation to the generation of the fog, as is manifest from the fact that, in a suitably designed embodiment, it either is projected in a totally different direction, for example north and south, while the alley runs east and west as in Figs. 4, 5 and 6, or that, if in the other apparatus it is projected in the very same direction as that which is projected under the partition 24 as some is in the apparatus illustrated in Figures 1, 2 and 3, wherein the upper current is projected in all directions horizontally, it issues where it would not touch the spatter plates even if the horizontal partition 24 were absent, being too remote therefrom and separated by the intervening body of air in the current of air which is rushing past the spatter plates and picking up the fog there generated.

In an alternative form sections of the partition 24 may be omitted, on those sides of the axis in which the air is to be projected in humidified form, as in Figures 4-6. In this case the top casing may be set at the proper height above the spatter plates for the full current of air needed for the fog to pass there, with free and immediate access for the fog to all parts of said current.

In either of these cases the fog which is generated on those sides of the axis in which the humidity is to be projected is picked up by the passing current of air and carried in the desired direction up and down the alley between machinery. In those directions from the axis in which the air is not to be projected humidified, e. g. toward the sides of the alley, the series of spatter plates at the periphery may be continued or discontinued. If discontinued the film of water which is thrown centrifugally from the edge of the rotating disk will merely strike the pan and flow back to the central well. On the other hand if the spatter plates are continued past such a section, the mist therein formed will float along in the air within the apparatus in the general direction of rotation of the disk until it comes to one of the openings from which humidified air is to be projected, and there it will be taken up by the current of flowing air. The speed in both cases will be enhanced by the frictional propulsion or drag of the plate upon the air which is within the apparatus and is next to the rotating disk. Meanwhile the air which is propelled downward by the fan 22 above on these sides of the axis where the pan has vertical peripheral walls 28, flows at a higher level between the said partition 24 and the said casing 26, and is deflected into horizontal direction by the said partition and is projected from the open lips

constituted by said partition and casing 26, so that it flows away from the apparatus laterally with respect to the alley and out over the machinery.

5 Under these circumstances units of the described apparatus set at intervals about a room will provide and maintain a desired condition of humidity generally throughout the room. The projection of the moist currents of air up and down the alleys prevents their impinging directly upon the machinery, or upon objects which may be above the machinery, while the lateral currents of air cause a continuous movement and circulation 10 of the air which is over the machinery and over the stock which is to be maintained of proper humidity, and thus cause, by indirect means, a slow and suitable distribution through the room of that air which is initially projected only along the alleys.

Upon the shutting off of water any time the fan or fans may continue in operation driving air alone in all directions.

The function of the lower fan, 23, may be understood by considering that if the central hole 25 be too small, not enough air may pass through it from the fan, and more of its blast will be diverted for projecting the currents of unhumidified air. In such cases 25 there may even be a slight up-draft through the hole 25 to supply the fan 22. In order to prevent this in cases where so large a proportion of air is to be used for dry distribution the fan 23 may be added as illustrated, 30 being set within the hole 25 and just below it and being of such size and power as is necessary to supply an adequate blast for carrying away the fog which is generated. It will be observed that the blast from this fan has 35 full access to the spatter plates and therefore readily picks up all of the fog which is there generated. However, if the central hole 25 be large enough, a sufficiency of air from the fan 22 will go down it and the fan 40 23 may be omitted.

For clearness in the drawings, the tie-bolts or connections which support the pan 10 in fixed relation to the top casing 26 and hold the partition 24 in place are not shown, 45 but it is to be understood that such means well known in the art may be provided.

I claim as my invention:

1. Apparatus for conditioning air in a room, comprising a rotating shaft with rotor 5 adapted to throw water centrifugally, a fan, and spatter plates arranged around the periphery of the rotor for generating a fog; combined with guides for the air from the fan, said guides being arranged below the 10 fan and dividing the path of air therefrom into two courses, one of which extends past said spatter plates with outlet through only a fractional part of the circumference of the apparatus, for distributing humidified air 15 in a particular horizontal direction, and the

other of which courses avoids said spatter plates for distributing only unhumidified air in a different horizontal direction.

2. Apparatus for conditioning air in a room, comprising elements arranged about a vertical axis, including a rotating vertical shaft with rotor adapted to throw water centrifugally, a fan, and spatter plates arranged around the periphery of the rotor for generating a fog; combined with a guiding partition positioned on one side of the apparatus below the fan arranged to keep a part of the air current away from the spatter plates and to guide it outward, thereby to distribute it unhumidified; and there being a discontinuance of said partition, on another side of the apparatus, where another part of the air current has free access to the spatter plates, and thereby is humidified and discharged thus into the 20 room.

3. Apparatus for conditioning air in a room, comprising elements arranged about a vertical axis, including a rotating vertical shaft with rotor adapted to throw water centrifugally, a fan, and spatter plates arranged around the periphery of the rotor for generating a fog; combined with a wall circumscribing said plates at a little distance and having openings for discharge of humidified air; whereby air bearing fog at places where there is no such opening is forced and guided circularly outside of said plates to the discharge opening which is next reached in the direction of flow.

4. Apparatus for conditioning air in a room, comprising elements arranged about a vertical axis, including a rotating vertical shaft with rotor adapted to throw water centrifugally, a fan, and spatter plates arranged around the periphery of the rotor for generating a fog; combined with guides arranged to define a course for air from the fan to said spatter plates with outlets through limited zones on opposite sides of the apparatus, and a partition set across a part of the delivery zone of the fan above the spatter plates and extending to a distance beyond the said plates, whereby a portion of the air from the fan is made to avoid 100 said spatter plates and is discharged unhumidified adjacent to the discharge of humidified air.

5. Apparatus for conditioning air in a room, comprising the combination, with 105 means for generating a fog, of guides arranged to define two air courses, one of which leads past said fog-generating means and has a limited horizontal breadth of discharge, and the other of which avoids the 110 zone of fog-generation and discharges in a different direction of the horizon from that in which the first mentioned course discharges.

6. Apparatus for conditioning air in a 115

room, comprising the combination, with air blowing and fog generating means, of guide walls defining two courses for the air thus blown, one of which leads to the zone of fog-generation, for humidifying its portion of air, and thence to a discharge mouth having a limited horizontal breadth of discharge, and the other of which courses avoids said zone of fog-generation and leads direct to a discharge mouth from the apparatus for delivering unhumidified air in a different horizontal direction from the horizontal direction of discharge of the first mentioned portion of air.

15 7. Apparatus for conditioning air in a room, comprising means in the apparatus for generating air currents; means arranged

to define an air course with discharge through limited portions of the complete horizontal zone, in different horizontal directions from said apparatus; means for generating a fog in said air course, whereby air therein entrains fog; means arranged to define another air course through which a portion of the air from said air current generating means is guided to avoid said fog and is discharged unhumidified in a different horizontal zone from the horizontal zone of discharge from the first mentioned course but in all directions of the horizon.

Signed at Boston, Massachusetts, this eleventh day of April, 1923.

FRANK B. COMINS
